(21) Appl. No.: **29/948,878**

Primary Examiner — George D. Kirschbaum

(22) Filed: **Jun. 24, 2024**

CLAIM

(51) LOC (15) Cl. 10-05

The ornamental design for a location indicating smoke detector as shown and described.

(52) U.S. Cl.

DESCRIPTION

USPC **D10/106.5**

(58) **Field of Classification Search**

USPC D10/106.1, 106.3, 106.5, 104.1

FIG. 1 is a front view of a location indicating smoke detector showing my new design;
FIG. 2 is a rear view of the location indicating smoke detector;
FIG. 3 is a right side view of the location indicating smoke detector;
FIG. 4 is a left side view of the location indicating smoke detector;
FIG. 5 is a top view of the location indicating smoke detector;
FIG. 6 is a bottom view of the location indicating smoke detector; and,

FIG. 7 is a top front side perspective view of the location indicating smoke detector.

The broken lines are illustrative of portions of the location indicating smoke detector forming no part of the claimed

design.
